UNITED STATES PATENT OFFICE.

GEORGE C. THOMPSON, OF EAST LIVERPOOL, OHIO, ASSIGNOR TO THE C. C. THOMPSON POTTERY CO., OF EAST LIVERPOOL, OHIO.

DESIGN FOR A CUP OR ANALOGOUS ARTICLE.

Application filed May 6, 1926. Serial No. 17,590. Term of patent 7 years.

To all whom it may concern:

Be it known that I, GEORGE C. THOMPSON, a citizen of the United States, residing at East Liverpool, in the county of Columbiana and State of Ohio, have invented a new, original, and ornamental Design for Cup or Analogous Article, of which the following is a specification, reference being had therein to the accompanying drawings.

The predominant feature of the design is the plurality of flat side wall surfaces arranged at angles to one another, and stopping short of the upper edge of the cup,

which edge is a true circle. The angular effect is also carried out in the cup handle.

In the drawings:

Figure 1 is a view in side elevation of the article, showing my new design.

Figure 2 is a top plan view thereof.

Figure 3 is a bottom plan view thereof.

I claim:

The ornamental design for a cup or analogous article, as shown and described.

In testimony whereof, I hereunto affix my signature.

GEORGE C. THOMPSON.
